UNITED STATES PATENT OFFICE.

JOHN F. RING, JR., OF AUBURN, NEW YORK.

GREASE PUMP.

Application filed May 13, 1920. Serial No. 381,172.

To all whom it may concern:

Be it known that I, JOHN F. RING, Jr., a citizen of the United States, residing at Auburn, in the county of Cayuga and State 5 of New York, have invented certain new and useful Improvements in Grease Pumps, of which the following is a specification.

This invention relates to grease pumps, and one of the objects of the invention is 10 to provide an improved device for filling transmission casings, differential casings and the like of motor vehicles and for lubricating parts of motors, machines and the like, which is so constructed that the grease or 15 oils can be quickly and easily forced from or into the same without any inconvenience on the part of the operator and which entirely eliminates the possibility of the grease or oils coming into contact with the hands 20 or clothing of the operator.

Another object of the invention is to provide an improved grease dispensing device in which the amount of grease being dispensed or placed in the device can be accurately determined, thereby insuring that 25 the correct amount of grease will be forced from the device to the parts being lubricated when the device is in operation.

Another object of the invention is to provide 30 an improved grease pump, which has been especially designed to supplant the grease pumps now on the market, in which considerable difficulties are experienced in the filling of the same and determining the 35 exact amount of grease contained therein or forced therefrom.

A still further object of the invention is to provide an improved grease pump of the 40 above character which is durable and efficient in use, one that is simple and easy to manufacture, and one which can be placed upon the market at a reasonable cost.

With these and other objects in view, the invention consists in the novel construction, arrangement and formation of parts, as will be hereinafter more specifically described, claimed and illustrated in the accompanying drawings, forming a part of this specification, in which drawings:

50 Figure 1 is a vertical longitudinal section through the improved grease pump.

Figure 2 is a top plan view of the same.

Figure 3 is a horizontal section taken on the line 3—3 of Figure 1.

55 Referring to the drawings in detail, wherein similar reference characters desig-

nate corresponding parts throughout the several views, the letter A generally indicates the improved grease pump which includes a cylindrical container 5 which is adapted 60 to receive the oil or grease to be dispensed. The cylindrical container 5 includes a bottom wall 6 and a removal top wall or cover 7. The removal top wall or cover 7 is held in place by means of removable fastening 65 elements 8 which extend through the top wall and in an outwardly extending annular flange 9 formed on the upper edge of the container. A removable partition plate 10 is arranged in the container 5 adjacent to 70 the upper end thereof and divides the container into an upper compartment 11 for the operation mechanism of the pump and a lower compartment 12 for the grease or oil. An annular shoulder 13 is formed on 75 the inner surface of the container and forms a seat for the partition 10. This partition is held in place against accidental displacement by means of a pair of tie rods 14, which also form guides for the piston or 80 plunger 15, which will be hereinafter more fully described. The lower ends of the tie rods 14 are threaded into upstanding washers 15' formed on the inner surface of the lower wall 6.

85 Retaining nuts 16 are threaded on the upper end of the tie rods and these nuts engage the upper and lower surfaces, respectively, of the partition plate.

The lower end of the cylinder is provided 90 with an outlet and inlet opening 17 in which is fitted a hose 18, the outer end of which carries a nozzle 19 which facilitates the placing of the grease or oil in the parts to be lubricated. The nozzle 19 may be provided 95 with any suitable form of shut off valve 20 so that after the desired amount of grease or oil has been forced into the part to be lubricated, the said valve can be actuated so as to prevent any further flow of the 100 oil therethrough.

To provide means for forcing the oil or 105 grease into or out of the cylindrical container, the piston or plunger 15 is provided, which is of such a size as to snugly fit the inner wall of the container. The upper or lower wall of the piston or plunger 15 is provided with specially treated cup washers 21 which absolutely preclude the passage of grease or oils around the piston and forms 110 a practically air tight joint therebetween. The axis of the plunger or piston 15 is pro-

vided with a vertically disposed hollow nut 22 which receives the rotatable threaded shaft or screw 23. The threaded shaft 23 is arranged at the vertical axis of the container 5 and is rotatably mounted at its upper and lower ends in suitable bearings 24 and 25 carried respectively by the lower wall 6 and the partition plate 10. To prevent the rotation of the piston or plunger on the shaft 23 10 when the same is rotated by means herein-after described, the same is provided with openings which are arranged on the opposite sides of the shaft 23 and these openings slidably receive the tie rods 14. Thus it can 15 be seen that the tie rods serve as a dual function, namely, to hold the partition plate in place and to guide the plunger or piston in its sliding movement, against rotation. The means provided for operating the shaft 20 23 includes a shaft 28 which is arranged at right angles to the shaft 23 and this shaft 28 is removably arranged in the compartment 11 and has its terminals mounted in suitable openings 29 formed in the container 25 5. One end of the shaft is provided with an operating crank 30 while the opposite end is provided with a removable lock nut 31. This shaft has removably secured thereto for rotation therewith a bevelled gear 32 which 30 meshes with a bevelled gear 33 secured to the upper end of the shaft 23. Thus it can be seen that by rotating the crank 30 the shaft 23 will be rotated which will slide the piston or plunger 15 up or down in the container according to the direction of rotation 35 of the crank. When it is desired to remove the shaft 28 so as to permit the partition plate 10 to be lifted out of the container, the retaining nut 31 is removed from the shaft 40 and the means provided for holding the gear 32 on the shaft is removable. It is then merely necessary to slide the shaft 28 out of the bearing.

The top plate or cover 7 is also provided 45 with a central bearing which slidably and rotatably supports a counter shaft 34, the lower end of which is provided with a bevelled gear 35 which meshes with the bevelled gear 32. The bevelled gear 35 is normally held in mesh with the bevelled gear 32 by means of an expansion coil spring 26 which is interposed between the top plate 7 and the hub of the bevelled gear 35. The outer end of the shaft 34 has secured thereto for rotation therewith a pointer or indicator 36 which is adapted to cooperate 55 with a plurality of graduations 37 on the top plate 7, which indicates the amount of grease being forced from or sucked into the 60 container.

In operation of the improved device, the nozzle 19 is inserted into the differential casing or other part which is to be lubricated, and the crank 30 is rotated which will 65 force the plunger 15 downwardly and thus

effectively push the grease from the container. As the shaft 23 is rotated the pointer 26 will be also rotated, and by glancing at the indicator and cooperating graduations the operator can at once determine the 70 amount of grease which is being dispensed. The cover 7 is graduated so as to indicate when five pounds of the grease has been dispensed and when a fraction of this amount has been forced from the container and it 75 is desired to move the pointer 36 back to the zero mark, it is merely necessary to lift the pointer 36 up which will move the gear 35 out of mesh with the gear 32. The shaft 34 can then be rotated so as to position the 80 indicator at the zero point.

After the grease or oil has been dispensed from the container, it is merely necessary to stick the nozzle 19 in the original barrel containing the oil or grease and rotate the crank 85 30 in an opposite direction from which it was previously rotated. This will force the plunger 15 gradually upward which will create a suction in the container below the same and thus effectively suck the oil or 90 grease into the container.

The lower wall 6 of the container is provided with three supporting legs 38 two of which are provided with casters 39 and it can be seen that the container can be moved 95 around the leg which is not provided with a caster as a pivot point.

From the foregoing description it can be seen that an improved oil pump has been provided, in which after the oil or grease 100 has been pumped from the original container, the same can be readily refilled by merely rotating the operating crank in a direction opposite to which it was operated for forcing the grease or oil therefrom. 105

Changes in details may be made without departing from the spirit or scope of the invention; but,

I claim:

1. A grease dispensing device comprising 110 a cylindrical container having an inlet and outlet opening formed in the bottom thereof, a removable partition wall carried by the upper end of the container, tie rods extending longitudinally through the container for 115 holding the partition plate in position, a sliding plunger mounted in said container, the plunger being adapted to receive the rods whereby rotation of the plunger in the container is prevented, and means for moving the plunger up and down in the casing. 120

2. A grease dispensing device comprising a cylindrical container, a partition plate in said container dividing the same into a pair of compartments, a plunger slidably mounted in one of said compartments, tie rods arranged to hold said partition in place and the plunger against rotation in said container, and means arranged in the other compartment for actuating said plunger. 125 130

3. A grease and oil dispenser comprising a cylindrical container, a vertical shaft arranged in the container, a plunger slidably mounted in the container having a nut arranged to receive the threaded shaft, guide rods for the plunger to prevent rotation thereof on said shaft, a right angularly disposed shaft arranged transversely to the screw threaded shaft, an operating crank for said second mentioned shaft, means operatively connecting the two shafts together, a pointer operatively connected to the second mentioned shaft, and means for permitting the resetting said pointer without the actuation of said piston.

JOHN F. RING, JR.
